ATTORNEY.

UNITED STATES PATENT OFFICE

VOLNEY A. McLAREN, OF WICHITA, KANSAS

DESIGN FOR A CHILI BOOTH

Application filed December 3, 1929. Serial No. 33,625. Term of patent 3½ years.

To all whom it may concern:

Be it known that VOLNEY A. McLAREN, a citizen of the United States of America, residing at Wichita, in the county of Sedgwick and State of Kansas, has invented a new, original, and ornamental Design for Chili Booths, of which the following is a specification.

Fig. 1 is a front view of the chili booth showing my new design.

Fig. 2 is a side view thereof.

I claim:

The ornamental design for a chili booth, as shown.

In testimony whereof I affix my signature.

VOLNEY A. McLAREN.
